(57) **CLAIM**

The ornamental design for a dashboard panel for vehicle, as shown and described.

DESCRIPTION

FIG. 1 is a front elevational view of a dashboard panel for vehicle showing my new design;

FIG. 2 is a right side elevational view thereof, the left side view being a mirror image thereof;

FIG. 3 is a top plan view thereof;

FIG. 4 is a bottom plan view thereof;

FIG. 5 is a rear elevational view thereof;

FIG. 6 is a front elevational view of a dashboard panel for vehicle with a transparent cover according to a second embodiment.

FIG. 7 is a right side view thereof, the left side view being a mirror image thereof; and,

FIG. 8 is a top plan view thereof.

The elements shown in broken lines form no part of the claimed design.
